(57) **CLAIM**

The ornamental design for an electric scooter, as shown and described.

DESCRIPTION

FIG. 1 is a perspective view of an electric scooter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 2; and,
FIG. 11 is an enlarged view of portion 11 in FIG. 2.

The dashed broken lines in the drawings depict portions of the electric scooter that form no part of the claimed design. The dot-dash broken lines showing of the enlargement indicia in FIGS. 1, 2 and 9-11 are shown for the purpose of illustrating the bounds of the enlargements and form no part of the claimed design.

1 Claim, 11 Drawing Sheets
